(57) **CLAIM**

The ornamental design for a lid for beverage container as shown and described.

DESCRIPTION

FIG. 1 is a top, front, right side perspective view of a lid for beverage container, showing the claimed design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof;

FIG. 6 is a bottom plan view thereof;

FIG. 7 is a bottom, rear, left side perspective view thereof;

FIG. 8 is a top, front, right side perspective cross-sectional view thereof, wherein a handle is bent upward from a periphery of the lid; and,

FIG. 9 is a right side cross-sectional view thereof, wherein a plug on the handle seals a drinking opening of the lid.
